UNITED STATES PATENT OFFICE.

EARL A. REED, OF OKEMAH, OKLAHOMA.

ROTARY WELL-DRILLING APPARATUS.

Application filed February 27, 1925. Serial No. 12,071.

The invention relates to improvements in a rotary well drilling apparatus.

It is an object of the invention to provide a well drilling apparatus in which large carriers can be utilized for supporting the cutters and detachably secured in the bit head by means of removable bearings.

In the use of rotary bit drills it has heretofore been customary in the art to manufacture the cutters from solid bar stock. As soon as the teeth are destroyed the cutters are useless, hence the material forming the body of the cutter is wasted.

This invention aims to utilize cutters manufactured from tubular stock by mounting said cutters on carriers or supports of a substantial diameter and in providing the bit head with removable bearings by means of which these large carriers may be removably supported in the head.

The invention more specifically relates to improvements in a bit head whereby the enlarged carriers for the cross cutter and the side cutters may be supported by removable bearings attached to and forming a part of the bit head thereby permitting cutters to be used that are made from tubular stock without necessitating the use of bushings, or small bearing pins.

In the drawings Figure 1 represents a view of a bit head with the cutters and their carriers removed showing the detachable bearing caps in position.

Figure 2 represents a view showing the bearing cap in attached position for supporting one of the side cutters.

Figure 3 discloses a view with the cutters in the drill head; and,

Figure 4 illustrates a slightly modified view of the invention.

Referring now more particularly to the drawings wherein like reference characters indicate corresponding parts, the numeral 1 designates a drill head that may be of a conventional type having arranged therein a central water feeding passage 2, an undercut pocket 3 and two side pockets 4 formed by the walls 5 and 6. The undercut pocket receives and supports a cross cutter carrier bearing a series of cutters while the side pockets receive the side cutters of a construction to be hereinafter described.

In the prior use of drills of this kind the cutters have generally been constructed from solid bar stock. As soon as the teeth are injured the cutter is no longer capable of use.

When discarded this means that the body material is wasted. When not so constructed it has been necessary to mount the cutters on bushings, which operation has not been satisfactory in all respects. The present invention comprehends the use of cutters made from tube stock which are mounted in the bit head without the use of bushings. To this end I utilize a carrier or bearing member for the cutters which is of a substantial diameter. For instance, the cross cutters 7 are supported by a carrier 8 extending through the bit head, which carrier is of a very substantial diameter. On this carrier 70 the cutters 7 loosely rotate. Interposed between the walls 5 and 6 at each side of the bit head there is also a carrier 9 of substantially the same diameter as the carrier 8 upon each of which carriers there is rotatably mounted a cutter 10 formed from tube stock.

In order to permit the use of carriers of a large diameter such as herein disclosed, it is preferable that improved means be provided for supporting said carriers in the drill head. With this in mind I provide around the lower part of the drill head a removable cap, collar or extension 11 having therein at each end the semi-circular cup-shaped openings 12 which align with semi-circular cup-shaped openings 13 in the lower part of the bit head. These openings, of course, receive the usual bearings. The sides of the drill head also have cup-shaped openings 14 which align with the cup-shaped openings 15 in the bearing cap. The bearing cap further has a series of shoulders 16 that enter complementary recesses 17 in the lower edge of the bit head to take lateral 95 stresses placed on the bearing cap. Fastening screws 18 pass through the cap and enter the drill head for the purpose of uniting the cap thereon.

It will furthermore be seen in Figure 2 that the side walls 5 of the drill head receive detachable bearings 20, having openings 21 therein to support the outer ends of the carriers for the side cutters. The carriers are formed with ears 23 which enter 105 pockets 24 in the side walls of the bit head and fastening screws 26 pass through these ears and the side walls of the bit head to retain the carrier in position and to permit it to be moved laterally from the bit head 110 when a carrier is being placed therein or removed therefrom.

From this description it will be seen that to assemble the drill the bearing cap 11 is first removed by a loosening of the screws 18. The large cross carrier 8 with its cutters is then inserted in the bottom of the bit head, the ends of this carrier resting in the semi-circular cup-shaped bearings 13. This carrier is retained in position by a dowel pin or the like and does not rotate. The carriers 9 for the side cutters 10 are also at this time inserted in position. The inner ends of these carriers are inserted in the semi-circular cup-shaped opening 15, one carrier being disposed at each side of the drill head. One of the removable bearings or brackets 20 is then inserted over the end of its carrier, the carrier, of course, at this time having loosely mounted thereon its cutter. The bearing 21 in this bracket receives the end of its carrier. The bracket is then moved into position shown in Figure 2 and the fastening screws 26 tightened to hold this bearing bracket in position. Dowel pins are provided to prevent a rotation of the side carriers. The bearing cap 11 is then inserted in position, the semi-circular bearings therein fitting over the various ends of the carriers, and the fastening screws 12 adjusted so as to unite this bearing cap to the bit head. The carriers with their cutters are thus held firmly in the bit head, it being apparent that these carriers are of a very substantial diameter, making it possible to use cutters constructed from tube stock without necessitating the use of bushings and that also the bit head is not unduly weakened in supporting such carriers. The cup shaped openings found in the removable cap 11 communicate with keyway slots 12' receiving keys 13', one of which is shown in Fig. 4 for the purpose of retaining the center and side carriers against rotation.

In Figure 4 I have shown a slightly modi-

fied form of the invention wherein the bearing cap does not surround the entire lower portion of the bit head, but in which structure a removable bearing cap 25 is utilized adjacent each opening in the bit head for one of the carriers. Each bearing cap is retained in position by screws 26, it being apparent that in this modified construction instead of utilizing a single bearing cap for all of the various bearings as shown in Figure 1, I employ a separate bearing cap for surrounding each bearing.

50

55

Having thus described my invention, what I claim is:

1. In a drill, the combination with a bit head having an open interior, a cross carrier disposed within the open interior of said head, cross cutters mounted on said carrier, a removable cap having in its upper edge a series of semi-circular openings corresponding to the openings in the lower edge of the drill head to form with such openings journals for the carrier, and fastening devices for securing said cap to the bottom of the drill head.

2. In a drill, a drill head, a center carrier, cutters on the carrier, said drill head having a series of semi-circular openings in the lower edge thereof, side cutter carriers for the drill head, side cutters on said carriers, a removable cap, said cap having openings therein corresponding to the openings in the lower edge of the drill head, means for securing the removable cap to the drill head whereby the openings in the drill cap are in alignment to provide journals for the center carrier and for one side of each of the side carriers, and removable bearings connected with the drill head for supporting the opposite sides of said side carriers.

In testimony whereof I affix my signature.

EARL A. REED.
